UNITED STATES PATENT OFFICE.

ROBERT T. PEIRCE, OF NEWPORT NEWS, VIRGINIA.

AUTOMATIC DUMPING-ELEVATOR.

1,007,483.

Specification of Letters Patent. Patented Oct. 31, 1911.

Application filed July 29, 1910. Serial No. 574,494.

To all whom it may concern:

Be it known that I, ROBERT T. PEIRCE, citizen of the United States, residing at Newport News, in the county of Warwick and State of Virginia, have invented certain new and useful Improvements in Automatic Dumping-Elevators, of which the following is a specification.

My invention relates to elevating mechanism and particularly to such hoisting mechanism in which a pivoted dumping bucket or carrier is used which is automatically rotated upon its pivot to a dumping position when the bucket or carrier reaches a predetermined elevation.

The primary object of the invention is the provision of a mechanism of this character in which the bucket or carrier is so mounted that it will dump beyond the plane of its travel and in which the bucket or carrier will normally be held in a vertical position either loaded or unloaded by the force of gravity.

A further object is to provide an automatic elevated dumping mechanism in which the carrier or bucket shall be automatically dumped without stopping the ascent of the carrier, thus obviating the shock and strain on the mechanism due to a complete stoppage of the hoisting carrier or bucket when it reaches the place at which it is to be dumped.

A further object is to provide in connection with the bucket or carrier a chute which when the carrier is lowered is automatically raised into such position that it will guide the contents of a cart into the bucket or carrier.

A further object is the provision of a dumping bucket or carrier mounted between vertical standards or guides which shall be particularly suitable for elevating materials of any kind in building construction and delivering said materials into a bin, chute or hopper, or on to the floor of the building, which mechanism shall be simple in construction, light in weight, positive in action and easily adapted to dump at any point.

Broadly considered, the invention comprises vertical guides between which the bucket operates, and a bucket which is eccentrically pivoted between these guides, both with relation to a plane cutting its vertical center and a plane cutting its horizontal center, the bucket thus remaining in a vertical position either when it is loaded or un-

loaded, suitable means being provided, adjustably mounted upon the vertical guides whereby the bucket may be rotated upon its axis at any predetermined point.

My invention is shown in the accompanying drawings wherein:

Figure 1 is a perspective view of my elevating mechanism. Fig. 2 is a vertical sectional view showing the bucket or carrier raised to its dumping position. Fig. 3 is a like view but showing the bucket or carrier lowered to its receiving position. Fig. 4 is a perspective view of the bucket or carrier detached from the supporting frame. Fig. 5 is a perspective view showing a modified manner of supporting the bucket.

Referring to the drawings 2 designates a base of any desired character but shown as formed of a rectangular frame composed of the opposite side bars 3 and the bars 4. Mounted upon the opposite sides of the frame and extending upward therefrom are the vertical standards or guides 5 which are of any desired height and which are connected at their upper ends by the spaced cross bars 6 between which are mounted pulleys 7 and 8, the pulley 8 being located midway between the standards or guides 5. It will be seen from Fig. 1 that the cross bars 6 extend out on one side beyond the adjacent standard or guide 5, and that the pulley 7 is mounted between these projecting extremities of the cross bars 6 so as to be supported beyond the outer edge of the adjacent guide 5.

Adjustably mounted upon the guides or standards 5 are the oppositely disposed brackets 9, one for each standard, these brackets being so mounted upon the standards that they may be adjusted vertically to any desired position and held in their adjusted position. As shown each of the brackets at its base is provided with a U-shaped flange 10 which embraces the corresponding guide or standard 5 so as to securely hold the bracket in position but at the same time to permit the bracket to be raised or lowered. The brackets 9 are connected by the transversely extending beam 105 or cross piece 11 which may be made of any suitable material and connected to the brackets in any suitable manner. This cross piece 11 or beam is beveled upon its upper and outer face as at 12, and suitably supported upon the cross piece 11 is the downwardly and outwardly inclined chute 13.

having the upwardly extending side walls 14. As shown, the cross piece or beam 11 is attached to the bracket 9 by means of bolts but any suitable manner of joining this cross piece and the bracket may be employed. The chute 13 may of course be attached to the cross piece or to the brackets in any desired manner, as by the bolts 13^a.

Attached to the inner face of the cross piece in any suitable manner are the vertically adjustable bucket engaging tripping arms 15. These are angular, their upper ends projecting over and in the path of the pins or lugs 22 on the bucket. The arms 15 are spaced from each other to permit the bucket to pass between them and are disposed at opposite ends of the transverse cross bar 11. These members 15 are vertically slotted so that they may be adjusted vertically upon the cross bar for a purpose to be later described. The bucket 16 is provided with the oppositely disposed trunnions 17 which are located to one side of the middle vertical plane of the bucket and preferably below the center of gravity. The trunnions are nearer to the dumping side of the bucket than to the opposite side, thus the bucket will normally retain the position shown in Figs. 1 and 3, whether the bucket be loaded or unloaded. Preferably the trunnions are disposed so low down upon the bucket that it requires but very little force to tip it, and yet are so disposed that the bucket will automatically return to its vertical position after the load has been dumped. The bucket is pivoted to a bail 18 forming a supporting yoke, which bail is U-shaped and extends over the bucket and down the sides thereof and is provided at its ends with the eyes 19 through which the trunnions 17 pass. This bail is provided on each arm with a plurality of U-shaped slides 20 which engage with the inside edges of the standards 5, as shown in Figs. 1 and 4. These slides act as guides for the bucket and are of such dimensions as to readily slide upward and downward upon the standards or guides 5 while at the same time holding the bail from any lateral movement.

Projecting outward on each side of the bucket near the upper end of the same are the stop lugs 21 which when the bucket is in its vertical position contact with the bail 18 so as to prevent the bucket rotating in one direction beyond a vertical position, thus providing means whereby the weight contained within the bucket, or the weight of the bucket itself, will normally hold it in a vertical position.

Projecting out from the sides of the bucket near the front thereof are the oppositely disposed lugs or pins 22 which as the bucket is raised are engaged by the inwardly projecting ends of the arms 15 and thus form a means whereby the bucket is tipped when

it has reached its dumping position. The bail 18 is attached to a flexible connection as for instance a wire cable 23 which passes up over the pulley 8, across and over the pulley 7 and then downward to any suitable position. It may be left free as illustrated in Fig. 1 so that it may be operated by hand, or the depending end of the cable may be attached to any suitable hoisting mechanism, not shown.

The operation of this portion of my invention will be obvious. As the cable 23 is pulled the bucket will be hoisted until a point is reached where the pins or lugs 22 engage with the inwardly projecting ends of the arms 15. As the bail moves upward, the arms 15 will act to rotate the bucket upon its trunnions and the bucket will take the position shown in Fig. 2, the end of the bucket resting upon the beveled face of the cross piece 11, the bucket then being in a discharging position and discharging its contents upon the chute 13. At this point the pins 22 have escaped beyond the inwardly turned ends of the tripping arms 15 and the bucket is free to continue its ascent, the pins 22 bearing against the guide 5 and forming stops preventing the further inversion of the bucket. As the bucket moves downward its forward end contacts with the cross bar 11 and it is turned upon its trunnions to a position where the weight of the bucket will tend to turn it into a vertical position, and it will retain this vertical position as shown in Fig. 3 until it reaches the bottom of the hoist. It will be seen that both in its loaded and unloaded position the bucket will normally remain vertical and, that it is rotated not by so pivoting the bucket that it is in unstable equilibrium and then tripping the bucket, but that it is rotated by coming in contact with stops mounted on the cross bar 11 and that it is rotated back to its vertical position by contacting with said cross bar.

In connection with my improved hoisting and dumping apparatus I have provided means whereby the contents of a cart may be guided into the bucket when the bucket or carrier has reached its lowered position. To this end I have mounted upon the bar 4 of the base 2 the upwardly projecting supports 25 which are formed with eyes at their upper ends within which is carried the rock shaft 26 having oppositely disposed pulleys 27 on its ends. Mounted upon this shaft is a chute 28 having sides 29 and passing over the pulleys 27 is a flexible connection 30 which passes downward over a pulley or through an eye 31 attached to the base, then upward, then outward and over a pulley 32 attached to the standard and then downward, the ends of the flexible connections being attached to a freely swinging bail 33 which depends beneath the path of travel of the bucket or carrier so that when the

bucket or carrier is lowered to its lowest position it will engage the bail 33 and the weight of the bucket or carrier will depress the bail, thus drawing upon the flexible connections 30, rotating the shaft 26 and raising the chute 28 to the position shown in Fig. 3 so that a cart 34 may have its contents directed immediately into the bucket. When the bucket or carrier is raised as shown in Fig. 2, the weight of that portion of the chute 28 which projects beyond the rock shaft 26 will cause the chute to fall to the position shown in Fig. 2, that is to a vertical position. It will be obvious that this chute 28 may be easily disconnected from the remainder of the mechanism when it is not desired to use it.

In Fig. 5 I show a modified form of my construction in which the elevator bucket, eccentrically pivoted as above described, is so mounted upon an ordinary elevator platform that it can be easily lifted off and the platform used for carrying other materials. The elevator platform is designated 35 and is provided with the usual vertical shaft 36 designed to engage vertical standards or guides upon which the elevator is mounted and connected at their upper ends by a cross bar 37 to which a flexible connection 38 is attached. The vertical members 36 are provided with the outwardly projecting brackets 39 which are slotted as at 40 to receive the trunnions 41 of a bucket 42. This bucket is constructed precisely similar to the bucket 16 shown in Fig. 1 and is provided with the stop lugs 43 and the outwardly projecting stop pins 44. It is to be noted particularly that the bail 18 in the first construction described is the equivalent for the supporting structure illustrated in Fig. 5. In other words that in Figs. 1 to 4 the bail 18 forms a supporting yoke for the bucket having a cross-piece and depending legs, and in Fig. 5 this supporting structure also consists of a cross-piece 37 and depending legs 36. The means for dumping the bucket 42 are precisely similar to those previously described and therefore need no specific illustration or description. The supporting members 36 of the elevator are intended to run between the guide supports 5, and the operation of the dumping bucket is precisely the same as that previously described. When the elevator has reached a predetermined point the arms 15 on the cross bar 11 will engage the pins 44 and rotate the bucket upon its trunnions to dump the same. In this construction the legs 36 extend down below the bucket and therefore the pins 44 contact with the legs 36 to act as stops. The pins 44 thus act in precisely the same manner as the pins 22 in the construction shown in Fig. 1 and it will be seen that it does not matter whether the stops are provided for engagement with the bail or sup-

porting yoke or whether these stops engage with the vertical guides. It is sufficient that means be provided to prevent the overturning of the bucket to a position shown in Fig. 2. Upon a downward movement of the elevator the bucket will be returned to its vertical position as illustrated in Fig. 5. When it is desired to use the elevator for carrying materials which are not to be dumped, it is only necessary to remove the bucket 42 from the brackets 39. It is obvious that various buckets or carriers might be used for elevating different kinds of materials. This modified form of my elevator is particularly useful in building construction where various kinds of materials have to be handled, such as bricks, lumber, mortar etc. For hoisting some of these materials the bucket is unsuited and the platform must be used, while other materials cannot be carried on the platform and the bucket must be used. It will be obvious that this bucket and the supporting brackets may be attached to any ordinary elevator or platform hoist.

It is to be noted that the modified form of my elevator is in essentials precisely the same form as that shown in Figs. 1 to 4. The supporting members 36 of the platform correspond in function to the bail shown in Figs. 1 to 4, and these supporting members 36 are guided upon the guides 5 in any suitable manner. In other words, in the modified construction the bail carries upon it a platform. It is particularly to be noted that there will be only a very slight jar (if desired) when the bucket is tripped. The pins 22 strike the inwardly projecting ends of the tripping arm 15 and the bucket is gently swung over against the weight of the load until it becomes overbalanced. At this point the front face of the bucket is but very slightly above the cross bar 11 and as a consequence has but little way to fall, if the tripping arms are adjusted at a relatively low point. If, however, the tripping arms are adjusted to their highest point the bucket will strike the cross bar with a greater shock. This is sometimes necessary where materials such as grouting or liquid cement are being dumped from the bucket as the jar will cause the detachment of cement or particles of grouting from the interior face of the bucket. This matter of the jar or shock, however, can be easily adjusted by adjusting the tripping members 15, as above referred to. Neither will there be any jar or shock as the bucket lifts. The face of the bucket will be supported upon the cross bar 11 as the rear end of the bucket continues its movement upward. The bucket will turn as the bail continues its movement upward until such a time as the pins or stops 22 engage with the standards 5, as shown in Fig. 2. This engagement oc-

curs just as the bucket is about to leave the cross bar. Thus there is no shock against these pins 22 and no liability to bend the same, as there would be if the bucket had 5 left the cross bar 11 before the pins 22 came in contact with the uprights 5.

It will be seen in the position shown in Fig. 2 or any position after the bucket is dumped that upon a lowering of the bucket 10 the front face of the bucket first strikes the cross bar 11. This holds the forward end of the bucket from any downward movement while the rear end moves down with the bail. As a consequence the bucket is given 15 an easy rotative movement until a point is reached where the bucket is overbalanced and returns to a vertical position. As the bucket becomes vertical the stops 21 engage with the bail 18, but as the bucket at this 20 time has deposited its load and is therefore relatively light, very little shock is communicated to the lugs 21.

It will be seen that it is necessary that the 25 distance between the pivotal point of the bucket and the upper edge of the front side should be greater than the distance between the standards 5 and the cross bar 11 so that when the bucket is turned the front end thereof will project beyond the plane 30 of travel of the front face of the bucket, in other words, shall project across the cross bar 11 so as to contact with the same when the bucket is lowered.

I have found my improved elevating apparatus particularly useful in building concrete structures where it is necessary that the semi-liquid concrete shall be mixed at the ground floor and carried up to the successive floors and there dumped. By reason 35 of the adjustability of the brackets 10 it is possible to adjust the point at which the bucket shall dump, and thus as each floor is constructed the brackets 9 are raised to the floor above. This invention can be also used 40 with a concrete mixer, the mixer dumping into the chute 28, and the buckets are raised and dump their contents into a wagon drawn beneath the chute 13. It will be obvious also that the construction is capable 45 of use in a large variety of other circumstances.

What I claim is:

1. In an automatic dumping elevator, a supporting yoke, hoisting means connected 55 to the yoke and a tilting carrier mounted on the yoke, the pivotal point of said carrier being below and between the center of gravity of the carrier and the dumping side thereof, and a stop on the carrier contacting 60 with the yoke when the carrier is in a vertical position to limit its rotative movement in one direction but permitting it to be rotated to a dumping position.

2. In an automatic dumping elevator, a 65 supporting yoke, hoisting means connected

to the yoke, a tilting carrier pivotally mounted on the yoke between a vertical plane cutting the center of gravity of the carrier and the dumping side thereof, a stop on the bucket disposed vertically above 70 the pivotal axis of the bucket and limiting the rotative movement of the carrier, and means projecting into the path of movement of the dumping side of the carrier for engaging the carrier as it is elevated and 75 rotating the same to a dumping position and engaging the carrier as it is lowered and rotating it to its vertical position.

3. In an automatic dumping elevator, a supporting yoke, hoisting means connected 80 to the yoke, a tilting carrier pivotally mounted on the yoke, the pivotal point of said carrier being located between a vertical plane cutting the center of gravity of the carrier and the dumping side thereof 85 and below a horizontal plane cutting said center, a stop on the upper portion of the carrier vertically disposed above the pivotal axis of the carrier and engaging the yoke to support the carrier in a vertical position 90 but permitting a rotation of the carrier to a dumping position, and means projecting into the path of movement of said dumping side of the carrier and for engaging the carrier as it is elevated to rotate the same 95 to a dumping position but permitting the upward passage of the carrier above said means and engaging the carrier as it is lowered to rotate it to its vertical position.

4. In an automatic dumping elevator, a 100 supporting yoke, hoisting means connected to the yoke, a tilting carrier in stable equilibrium pivotally mounted on the yoke, and relatively fixed means disposed in the path of travel of the dumping side of the carrier for engaging the carrier as it is elevated, rotating the carrier to a dumping position but permitting the upward passage 105 of the carrier above said means and rotating the carrier to its vertical position 110 as the carrier is lowered.

5. In an automatic dumping elevator, a supporting yoke, a carrier pivotally mounted on the yoke eccentric to the center of gravity of the carrier, a stop on the carrier contacting 115 with the yoke when the carrier is in a vertical position but permitting the carrier to be rotated to a dumping position, a stop preventing the undue rotation of the carrier, oppositely disposed vertical guides with 120 which the yoke engages, hoisting means connected to the yoke, and a tripping device supported upon the guides and engaging said carrier as the carrier moves upward to rotate the same into a dumping position but 125 permitting the continued movement of the carrier and engaging said carrier as it moves downward to return it to its vertical position, said vertical guides extending above the tripping device. 130

6. In an automatic dumping elevator, oppositely disposed vertical guides, a supporting yoke moving between said guides and having sliding engagement therewith, a carrier eccentrically pivoted between the arms of the yoke, hoisting means connected to the yoke, a tripping device vertically adjustable upon the guides, said tripping device projecting into the path of movement of the carrier and acting to rotate the same to a vertical position as the carrier is raised but permitting the further upward movement of the carrier and engaging said carrier to return it to its vertical position upon a downward movement of the carrier.

7. In an automatic dumping elevator, oppositely disposed vertical guides, a supporting yoke slidably mounted between said guides, hoisting means connected to said yoke, a carrier eccentrically pivoted to the yoke and having oppositely disposed pins projecting outward from its sides, a chute adjustably mounted upon the guides, and inwardly extending oppositely disposed tripping members mounted at the entrance to the chute and projecting into the path of movement of the said pins upon the carrier whereby the carrier may be rotated into a dumping position when it is lifted into engagement with the pins.

8. In an automatic dumping elevator, oppositely disposed guides, a supporting yoke mounted between the guides and having sliding engagement therewith, hoisting means attached to the yoke, a carrier bucket pivotally mounted between the arms of the yoke and having pins projecting out from its opposite sides, stops on the bucket engaging with the yoke to limit the rotative movement of the bucket in one direction, brackets adjustably mounted upon the guides, a chute mounted upon the brackets, and tripping members also supported by the brackets and projecting inward into the path of movement of the pins on the bucket, said tripping members being adapted to engage with the pins to rotate the bucket to a dumping position but permitting the further upward movement of the bucket and means engaging the said bucket to rotate the same to a vertical position upon a downward movement of the bucket past the tripping members.

9. In an automatic dumping elevator, oppositely disposed guides, a supporting yoke mounted upon the guides and having sliding engagement therewith, a hoisting cable attached to the supporting yoke, a bucket pivoted to said supporting yoke, the pivotal axis of the bucket being eccentric to the center of gravity of the bucket, stops for limiting the rotative movement of the bucket in one direction but permitting its movement in the other direction, lugs projecting from the bucket near the front there-

of, and oppositely disposed angular tripping members spaced from each other a distance sufficient to permit the bucket to pass between them, the angular ends of the tripping members extending into the path of movement of the lugs on the bucket, and a bar extending between the tripping members and supporting the bucket as the bucket is rotated by engagement with the tripping members, said bar acting to return the bucket to its vertical position upon a downward movement of the bucket.

10. In an automatic dumping elevator, oppositely disposed guides, a supporting yoke mounted between the guides and slidably engaged therewith, hoisting means connected to the yoke, a bucket pivoted to said yoke, the pivotal axis of the bucket being located to one side of the center of gravity of the bucket, oppositely disposed lugs projecting out from the opposite sides of the bucket near the front thereof, brackets mounted on the vertical guides, a cross bar connecting the brackets, and angular members mounted on the ends of the cross bar and spaced from each other a distance slightly greater than the width of the bucket, the angular ends of said members being adapted to engage with the pins on the bucket as the bucket is raised to rotate the bucket into a dumping position, said cross bar supporting the bucket when so rotated and acting to return the bucket to its original vertical position when the bucket is lowered.

11. In an automatic dumping elevator, oppositely disposed vertical guides, a supporting yoke having sliding engagement with the guides, hoisting means connected to the yoke, a tilting carrier pivotally mounted on the yoke, the pivotal axis of the carrier being eccentric to the center of gravity of the carrier, a stop on the side of the carrier engaging with the yoke to limit the rotation of the bucket in one direction but permitting its rotation in the opposite direction, an outwardly projecting lug on the side of the carrier near the front thereof, adjustable brackets mounted upon the guides, a cross bar connecting said brackets, the face of said cross bar being downwardly and outwardly beveled, a downwardly and outwardly extending chute attached to the cross bar, an angular tripping member attached to one end of the cross bar, the angular end of the member extending inward in the path of travel of the lug on the bucket and adapted to engage the lug to rotate the bucket to a dumping position but permitting the continued upward passage of the bucket, said cross bar engaging the bucket upon its descent to rotate it into a vertical position.

12. The combination with oppositely disposed vertical guides and a carrier vertically movable between said guides, of a

rock-shaft supported adjacent to the lower ends of the guides and to one side of the path of travel of the carrier, a chute mounted intermediate of its ends upon said rock-shaft, said chute being counter-balanced at its outer end so as to hold the chute in a depending vertical position, and means connected to said rock-shaft for rotating the rock-shaft upon the descent of the carrier 10 to its lowermost position to bring the chute into an upwardly extending angular position with its end projecting over the mouth of the carrier.

13. The combination with oppositely disposed vertical guides, of a bucket vertically movable between said guides, one side of said bucket being shorter than the other, a rock-shaft supported adjacent to the lower ends of the guides and to one side of the 20 path of travel of the bucket, a chute pivotally supported upon the rock-shaft and having a counter-weighted outer end, and means disposed at the lower ends of said guides and in the path of movement of the bucket for rotating said rock-shaft when the bucket has fully descended to move the chute into an angular position with its end projecting over the shorter side of said bucket.

14. The combination with oppositely disposed vertical guides and a bucket vertically movable therein, of a rock shaft mounted parallel to the path of movement of the bucket but to one side thereof, a chute 35 attached to the rock shaft and the inner end of said chute projecting beyond the rock shaft, means for holding the chute in a vertical position, pulleys mounted upon the ends of the rock shaft, flexible connections 40 passing over said pulleys and adapted to be wound upon the same, and a bar suspended from said flexible connections and extending across the path of movement of the bucket adapted to be depressed by the bucket when 45 the bucket is lowered to rotate the rock shaft and raise the chute into an upwardly and outwardly inclined position.

15. In an automatic dumping elevator, vertical guides, a supporting member vertically movable along said guides, a carrier pivoted to the supporting member for a rotative movement into a vertical or dumping position, the pivotal point of said carrier being below the center of gravity of the carrier 55 and between said center and the dumping side thereof, and fixed means mounted on the guides for engaging said carrier to rotate the same to a dumping position but permitting the carrier to move upward 60 above said means and engaging with the carrier as it is lowered to rotate it to a vertical position.

16. In an automatic dumping elevator, vertical guides, a supporting member vertically 65 movable between said guides, a car-

rier pivoted to the supporting member for a rotative movement into a vertical or dumping position, the pivotal point of said carrier being located below the center of gravity thereof and between said center and the dumping side of the carrier and means mounted on the guides disposed within the path of movement of the carrier for engaging said carrier to rotate the same to a dumping position but permitting the carrier to move upward above said means and engaging with the carrier as it is lowered to rotate it reversely into its vertical position. 75

17. In an automatic dumping elevator, vertical guides, a supporting member movable between said guides, a carrier pivotally mounted upon the supporting member, the pivotal axis of said carrier being to one side of a vertical plane cutting the center of gravity of the carrier and below a horizontal plane cutting said center of gravity, a stop engaging with the supporting member for limiting the rotation of the carrier in one direction, a projection on the carrier disposed adjacent to the front thereof, and a fixed tripping member located in the path of movement of the carrier and adapted to engage with said projection to tip the carrier to a dumping position as the carrier moves upward, said projection when the carrier is tipped to a dumping position engaging with the supporting member to form a stop preventing the further rotation of the carrier. 80 85 90 95

18. In an automatic dumping elevator, oppositely disposed vertical guides, a supporting member vertically movable between said guides, a carrier pivoted to the supporting member for rotative movement, the pivotal axis of the carrier being disposed below and to one side of the center of gravity of the carrier, a stop projecting out from the carrier adapted to engage the supporting member to normally hold the carrier in a vertical position, a projection on the carrier 100 located near the front of the same, a transversely extending bar supported adjacent to the path of travel of the carrier but not in said path, a tripping member mounted on said transverse bar and projecting into the path of movement of the projection on the carrier and adapted to trip the carrier as the carrier moves upward, said bar acting to return the carrier to its normal position as it moves downward after being 105 tripped, the projection on the carrier acting as a stop limiting the rotative movement of the carrier. 110 120

19. In an automatic dumping elevator, a supporting yoke, hoisting means connected to the yoke, a carrier pivotally mounted on the yoke, the pivotal point of said carrier being on one side of a vertical plane cutting the center of gravity of the carrier and toward the dumping side of the carrier, and 125 130

a stop on the carrier, between the dumping side and said vertical plane, contacting with the yoke when the bucket is in a vertical position to limit its rotative movement in 5 one direction and hold the carrier in a vertical position but permitting the carrier to be rotated toward the dumping side to a dumping position.

20. In an automatic dumping elevator, a 10 supporting yoke, hoisting means connected to the yoke, a tilting carrier pivotally mounted on the yoke, the pivotal point of said carrier being between a vertical plane cutting the center of gravity and the dumping side of said carrier and below a horizontal plane cutting said center of gravity, a 15 stop on the carrier contacting with the yoke when the carrier is in a vertical position to limit its rotative movement in one direction 20 but permitting it to be rotated to a dumping position, a stop on the carrier preventing the complete inversion thereof, and a tripping member disposed adjacent to the dumping side of the carrier and engaging 25 the inverted carrier as it moves downward to return it to a vertical position.

21. In an automatic dumping elevator, a bail, hoisting means connected to the bail, a 10 tilting carrier pivotally mounted on the bail, the pivotal point of said carrier being 20 located between a vertical plane cutting the center of gravity of the carrier and the dumping side of the carrier, a stop on the upper portion of the carrier vertically 25 disposed above the pivotal axis thereof and en-

gaging the bail-supporting carrier in a vertical position but permitting a rotation of the carrier in one direction to a dumping position, a transversely extending bar 40 mounted to one side of the path of travel of the carrier and having tripping members projecting to points on either side of the path of travel, and lugs projecting from the carrier adapted to be engaged by said tripping fingers as the carrier moves upward 45 to invert the carrier, said lugs limiting the dumping movement of the carrier.

22. In an automatic dumping elevator, a bail, a carrier pivotally mounted on the bail eccentric to the center of gravity of the 50 carrier, a stop on the carrier engaging with the bail when the carrier is in a vertical position but permitting a rotation of the carrier to a dumping position, hoisting means connected to the bail, lugs projecting laterally from the carrier, tripping members supported in the path of movement of the lugs adapted to engage with the same and overturn the carrier, said members being vertically adjustable, and a transverse bar 55 upon which the tripping fingers are mounted and adapted to support the end of the carrier as it is overturned.

In testimony whereof I affix my signature in presence of two witnesses.
